US00D510289S

(12) **United States Design Patent** (10) Patent No.: **US D510,289 S**
 Dueker et al. (45) Date of Patent: **** Oct. 4, 2005**

(54) **ILLUMINATED SIGNALING DEVICE**

(75) Inventors: **Kenneth S. Dueker**, Atherton, CA (US); **Paul M. Hagelin**, Saratoga, CA (US); **Troy J. Edwards**, Campbell, CA (US); **Russell E. Tavernetti**, San Carlos, CA (US)

(73) Assignee: **PowerFlare Corporation**, Menlo Park, CA (US)

(**) Term: **14 Years**

(21) Appl. No.: **29/190,129**

(22) Filed: **Sep. 15, 2003**

(51) LOC (8) Cl. **10-07**

(52) U.S. Cl. **D10/111; D10/109**

(58) Field of Search .... **D10/114, 113, D10/109, 115; D26/39; 340/815, 432, 908.1, 815.03, 760-761, 767, 782, 471, 473; 315/174, 200 A; 362/157, 800**

(57) **CLAIM**

The ornamental design for an illuminated signaling device, as shown.

DESCRIPTION

FIG. 1 is an isometric view of the embodiment.

FIG. 2 is a top view of the embodiment.

FIG. 3 is a bottom view of the embodiment.

FIG. 4 is a front view of the embodiment.

FIG. 5 is a left view of the embodiment.

FIG. 6 is a right view of the embodiment; and,

FIG. 7 is a back view of the embodiment.

1 Claim, 3 Drawing Sheets

FIG. 1

FIG. 2

FIG. 3

FIG. 4

FIG. 5

FIG. 6

FIG. 7
